WILLIAM C. HUEBNER, OF BUFFALO, NEW YORK, ASSIGNOR TO HUEBNER-BLEISTEIN PATENTS CO., OF BUFFALO, NEW YORK.

HOLDING MEANS FOR PHOTOSENSITIVE PLATES AND THE LIKE.

1,391,116.

Specification of Letters Patent. Patented Sept. 20, 1921.

Application filed February 27, 1919. Serial No. 279,492.

To all whom it may concern:

Be it known that I, WILLIAM C. HUEBNER, a citizen of the United States, residing at Buffalo, in the county of Erie and State of New York, have invented a new and useful Improvement in Holding Means for Photosensitive Plates and the like, of which the following is a specification.

This invention relates to photographic printing apparatus of the kind used for producing photographic prints upon the photosensitive or sensitized surfaces of metal or other plates which are afterward suitably finished and used for printing in one or more colors. More particularly the invention relates to improvements in the holders or means used for mounting such sensitized plates in the photographic printing apparatus and other apparatus used for coating the plates, or for other purposes in connection with the use of such plates.

The objects of the invention are to provide means whereby a sensitized metal plate or analogous, thin plate or sheet can be quickly and easily secured in the required position on the holder by which the plate is mounted in the photographic printing apparatus or other apparatus, and which enables a plate to be repeatedly placed in precisely the same position in the holder and different plates to be placed in exactly corresponding positions in the same or different holders; also to provide opposite edges of the plate with attached bars or reinforcing strips which facilitate the mounting of the plate in and its removal from the holders, and which also serve to determine the exact location of the gripper edge and side guide edge of the printing plate in the holder and also to reinforce and protect the edges of the plate and prevent the plate from being creased or dented in handling and manipulating the same; also to provide means which enable the plate holder to be quickly and easily mounted removably in predetermined position on the support of the photographic printing apparatus or other apparatus; also to provide the plate holder with desirable means whereby the plate can be stretched taut and smoothly in the holder; and also to improve the holders or holding means for printing plates and the like in the respects hereinafter described and set forth in the claims.

In the accompanying drawings:

Figure 1 is a front or face view showing a sensitized plate holder or holding means embodying the invention mounted on the plate holder support of a photographic printing machine.

Fig. 2 is a sectional elevation thereof on line 2—2, Fig. 1.

Fig. 3 is a fragmentary enlarged sectional elevation showing a modified form of holder.

Fig. 4 is an enlarged sectional elevation showing the securing means for one edge of the plate.

Fig. 5 is an enlarged sectional plan view on line 5—5, Fig. 3.

Fig. 6 is a broken plan view, partly in horizontal section of a plate holder and a support therefor.

Fig. 7 is a front elevation of a holder used for supporting the plate in a coating or sensitizing machine.

Referring first to Figs. 1 and 2, A represents the sensitized plate, B a holder on which the sensitized plate is secured and stretched taut, and C a frame, support or carriage on which the plate holder B is mounted, preferably removably. This support or carriage may be either the support on which the plate holder is mounted in a photographic printing machine for holding the sensitized plate in contact with a transparent negative or printing plate; or it may be the supporting part on which the plate holder is mounted in a machine for coating or sensitizing the plate; or the supporting part of other apparatus in which it may be necessary to mount the plate for any purpose in connection with the preparation or use of the same. The support can be of any suitable construction, depending upon its purpose. The plate holder B preferably comprises a rectangular, open frame composed of parallel longitudinal or upper and lower bars 1 and 2 rigidly connected by end bars or rods 3. In the holder shown in Figs. 1 and 2 the sensitized plate A is secured at one edge to the stationary upper bar 1 of the plate holder and at its opposite edge to an adjustable holding bar 4 which is movable on the end bars 3 of the holder toward and from the stationary bar 1.

The opposite edges of the sensitized plate which are secured to the opposite holding bars or members 1 and 4 of the plate holder

have fixed thereto or formed thereon, marginal reinforcements which coöperate with the holding bars 1 and 4 of the plate holder for securing the plate on the plate holder. 5 These reinforcements also serve to stiffen the edges of the plate and hold the same straight so as to prevent deformation or injury to the edges of the plate and prevent the plate from being creased, dented, buckled, 10 or otherwise injured in placing the plate in and removing it from the holder or otherwise handling the plate. As shown, each of these reinforcements consists of two narrow, metal bars 5 and 6, between which the edge 15 of the sensitized plate is clamped and securely held by bolts 7 passing through the two clamping bars. The reinforcements could be differently constructed and secured to, or formed on the edges of the plate. The holding bars or members 1 and 4 of the plate holder to which the opposite edges of the plate are attached are each preferably provided with a longitudinal recess 8, see Fig. 4, adapted to receive the reinforcing bars on 20 the edge of the sensitized plate. As shown in Fig. 4, this recess is provided with an undercut or shouldered front edge 9 and at its rear edge is provided with an overhanging flange 10 which may be a separate bar bolted to the holding bar, or may be otherwise formed or secured thereon. In order to secure the edge of the sensitized plate to one of the holding bars of the plate holder, it is only necessary to slip the reinforcement on 25 the edge of the plate downwardly at an inclination, into the recess 2 under the overhanging rear edge of the recess, lower its front edge into the recess and then move it forward until the front edge of the lower bar 6, which has a shape complementary to the front edge of the recess, enters the undercut front edge of the recess. The reinforcing bars are retained in this position by the tension on the sensitized plate and the plate is 30 thus securely retained in the plate holder without the manipulation of any fastening or securing devices. The plate is released by reversing this action or by slipping the reinforcing bars backwardly in the recess until 35 the front edge of the lower bar is disengaged from the undercut edge of the recess and then lifting the bars out of the recess. The opposite edge of the sensitized plate is preferably similarly secured to and removed 40 from the other holding bar of the plate holder. The marginal portions of the sensitized plate pass over and bear on the edges or corners 11 of the holding bars, and these edges are raised or so disposed relatively to 45 the other portions of the holder and the plate-securing means that the outer surface of the plate is held in a plane located outwardly beyond the plate-securing means and other parts of the holder. Therefore, if a 50 negative or printing plate contacting with

the sensitized plate A should extend beyond the edges of the latter, it could not engage any part of the holder and thus prevent perfect contact of the two plates with each other. 70

The sensitized plate is preferably provided with register marks 12, Fig. 1, with which coöoperating marks on the reinforcing bars 5 are placed in register when securing the reinforcing bars on the sensitized plate, so 75 that if the plate is then secured in the plate holder B with the reinforcing bars in a predetermined position, the sensitized plate will always occupy precisely the same position in the plate holder. For the purpose of insuring such accurate positioning of the plate in the plate holder, each holding bar of the plate holder is provided at one end of the recess 8 with a stop or part 13 against which one end of the reinforcing bar is adapted to 80 abut and the bar is shoved endwise into firm contact with the stop by a pressure device 14 at the opposite end of the plate holder. This pressure device as shown in the drawings consists of a screw passing through a 85 threaded lug 15 on the attaching bar and adapted to engage the adjacent end of the marginal bar and force the same endwise by turning the screw. The sensitized plate is accurately positioned in the plate holder by 90 engaging the reinforcement at one edge of the plate in one of the holding recesses of the plate holder and forcing the marginal bar over against the stop 13 which definitely locates this edge of the printing plate exactly in the intended position. The reinforcement at the opposite edge of the sensitized plate is then similarly secured in the recess in the adjustable holding bar of the plate holder and this bar is then moved to stretch 95 the plate taut. 100

The adjustable holding bar 4 is preferably provided at its ends with suitably pivoted guide blocks 16 arranged to slide on the end bars 3 of the plate holder and these guide 110 blocks are actuated by screws 17 to move the adjustable bar for stretching the sensitized plate. The screws 17 are suitably journaled on the plate holder, preferably in bearings 18 and 19 at the opposite ends of 115 the screws and the screws turn in threaded nuts 20 which are seated in cylindrical holes in the guide blocks. The nuts are normally held from turning by set screws 21 or other suitable means, but by loosening the set 120 screws the nuts can be turned so as to set the stretching bar 4 accurately into, or slightly out of parallelism with the opposing holding bar, as may be necessary to insure the proper, smooth stretching of the sensitized plate throughout after the adjustable 125 bar has been moved by turning the screws 17. The pivoted guide blocks permit the adjustable holding bar to be set at a slight inclination from a perpendicular to the 130

- guide rods 3 without causing the guide blocks to bind on the rods. The operating screws 17 can be turned simultaneously by any suitable connecting mechanism, such as a shaft 22 which is journaled on the lower bar 2 of the plate holder and is connected by spiral pinions 23 with the lower ends of the two screws. The connecting shaft is connected by spiral pinions 24 to an operating shaft 25 which can be turned by a crank or other suitable means. The adjustable holding bar 4 can be quickly moved by turning the single operating shaft 25 which causes a simultaneous rotation of the screws 15 and movement of the opposite ends of the adjustable bar. After thus moving the bar 4 to tighten the plate, one or the other of the nuts 20 can be turned, if necessary, in order to place equal tension on the opposite ends of the plate and prevent any wrinkling or unevenness in the plate. This construction enables a quick, perfect tightening of the plate. 26 represents screws which extend through holes in the lower bar 2 of the plate holder and are screwed into threaded holes in the adjustable holding bar 4. After the adjustable holding bar has been adjusted, as explained, these screws can be inserted and tightened to straighten the holding bar in case the same is sprung out of a true straight line by the strain of the sensitized plate.
- The plate holder B is secured on the support C, preferably removably, in the following manner:—The upper bar 1 of the plate holder is provided with a longitudinal shoulder, see Fig. 2, which is adapted to rest on a horizontal ledge or shoulder 28 on the front side of the upper bar of the support C. 30 The plate holder is placed with its shoulder resting on this ledge and is moved thereon endwise over against a stop or abutment 29 on the support at one end of the plate holder by a screw-operated wedge block 30, see Fig. 6, adapted to engage the opposite end of the upper bar of the plate holder. The faces on the ends of the plate holder which contact with the abutment 29 and the wedge block 30 are preferably inclined in two directions, that is, both horizontally and vertically, as indicated in Figs. 1 and 6, so that when the wedge block 30 is forced inwardly by its operating screw 31 the upper bar of the plate holder will be pressed firmly down 35 on the supporting ledge 28 and also inwardly against the outer face of the support. This insures that the plate holder will be held firmly on the support and always secured thereon in exactly the same position. After the upper edge of the plate holder has been thus secured, the lower edge is similarly secured by operating a screw 32 which forces a wedge block against the adjacent end of the lower bar of the plate holder and forces 40 this bar over against an abutment 33 on the support at the opposite end of the plate holder. This abutment and the wedge block are also preferably inclined so as to press the lower edge of the plate holder firmly back against the outer face of the support. 45
- In the plate holder B' shown in Figs. 3 and 7, both of the holding bars 4^a and 4^b for the opposite edges of the plate are adjustable toward and from each other on the end bars 3^a of the holder frame. This construction of the holder is desirable for use with plates which differ considerably in width. The bar 4^b is adapted to be set nearer to or farther from the other bar 4^a to suit the width of the plate being used, and 50 can be secured in place by any suitable means, such, for instance, as set screws 34 passing through the guide blocks for this bar and adapted to enter notches 35 in the end bars 3^a of the holder frame. The other 55 holding bar 4^a is moved to stretch the plate taut by screws 36 at the ends of the holder, as in the case of the holder shown in Figs. 1 and 2, but the screws 36 shown are not connected, but are adapted to be turned independently by a crank or device applied to the ends of the screws. The sensitized plate is secured to the two holding bars in the manner before explained by seating the reinforcing bars on the opposite edges of the 60 plate in the recesses in the holding bars. This type of holder enables the plates to be secured in the same with the center of the plate coincident with the center of the holder, and holders of this sort are suitable 65 for mounting the plates in a plate-sensitizing or coating machine in which the center of the plate should conform to the center of rotation of the machine.
- The described construction of the plate 70 holder and means for securing the plate thereon enable the gripper edge of the sensitized plate to be placed exactly in a predetermined position in the photographic printing machine irrespective of the size of 75 the plate used, and also makes it possible to quickly, conveniently and accurately mount the plate for register in a printing press provided with similar holding means for the reinforced gripper edge of the plate. It is 80 a recognized fact that the gripper edges of metal plates become mutilated during repeated use in the various machines in which the plates are used, particularly on the printing press. The resulting irregular edges of 85 the plates are difficult to straighten out for quick and easy mounting in the plate holders of the photographic printing machines. This difficulty is eliminated and greater convenience provided for handling the plates to 90 meet the special requirements in the various operations necessary to the preparation and use of the plates by providing the plates with the described reinforcements or bars on their edges. These bars insure the same relative 95

position of the plate in the holders of the different machines. It is desirable in some photographic printing machines to have the gripper edges of sensitized plates of various sizes occupy exactly corresponding positions, irrespective of the position that the back edges of the plates assume. This is necessary to conform to certain layout conditions and for convenience in composing photographic images on various sized plates. Sometimes it is necessary to remove a holder with the sensitized plate thereon from the photographic printing machine for the purpose of developing the plate and resensitizing it for placing a corrected image in the precise location on the plate. In such a case the holder with the plate thereon can be mounted in the sensitizing machine for sensitizing the plate, and can then be replaced in the photo-printing machine in exactly the same position it previously occupied. These various results are possible with the described plate holding means. The holder is also adapted for holding a layout sheet, key sheet or stick up plates in exactly the required position, because of the edge reinforcing or attaching bars which enable all of the plates or sheets to be mounted in exactly registering positions, so that no time is lost between jobs by an undue length of make-ready time. The plates with the attached reinforcing or edge bars can also be readily stored in the minimum space in suitable light proof compartments to protect the sensitized surfaces from light, and the edge reinforcements or bars make it possible to handle thin, metal plates with the minimum danger of creasing, denting or buckling the plates.

I claim as my invention:

- 40 1. A holder for a thin sensitized printing plate, comprising a frame having holding members for opposite edges of the plate, projecting reinforcements on said plate adjacent opposite edges thereof, and means for detachably securing said reinforcements to said holding members.
- 45 2. A holder for a thin sensitized printing plate, comprising a frame having holding members for opposite edges of the plate, projecting reinforcements on said plate adjacent opposite edges thereof, means for detachably securing said reinforcements to said holding members, and means for applying stress to the plate to make the plate taut.
- 50 3. A holder for a thin sensitized printing plate, comprising a frame having holding members for opposite edges of the plate, a projecting reinforcement on said plate adjacent one edge thereof, means for detachably securing said reinforcement to one of said holding members, means for securing the opposite edge of the plate to the other holding member, and means for relatively spreading said holding members to make the plate taut.
- 55

4. A holder for a thin sensitized printing plate, comprising a rectangular frame provided with connected holding members for opposite edges of the plate, a projecting reinforcement on said plate adjacent one edge thereof, one of said holding members having parts which said reinforcement engages for detachably securing the plate to said holding member, and means for securing the opposite edge of the plate to said other holding member. 70 75

5. A holder for a thin sensitized printing plate, comprising a rectangular frame provided with connected holding members for opposite edges of the plate, a projecting reinforcement on said plate adjacent one edge thereof, one of said holding members having parts which interlock with said reinforcement for detachably securing the plate to said holding member, and means for securing the opposite edge of the plate to said other holding member. 80 85

6. A holder for a thin sensitized printing plate, comprising a rectangular frame provided with connected holding members for opposite edges of the plate, projecting reinforcements on said plate adjacent opposite edges thereof, and said holding members having portions which interlock with said reinforcements for detachably securing the plate to said holding members. 90 95

7. A holder for a thin sensitized printing plate, comprising a rectangular frame provided with connected holding members for opposite edges of the plate, projecting reinforcements on said plate adjacent opposite edges thereof, said holding members having portions which interlock with said reinforcements for detachably securing the plate to said holding members, and means for relatively spreading said members for making the plate taut. 100 105

8. A holder for a thin sensitized printing plate, comprising a rectangular frame provided with connected holding members for opposite edges of the plate, a projecting reinforcement on said plate adjacent one edge thereof, one of said holding members having parts which said reinforcement engages for detachably securing the plate to said holding member, and means for securing the opposite edge of the plate to said other holding member, said plate being supported by said holder with its outer face in a plane disposed outwardly beyond the plate securing means and other parts of the holder. 110 115 120

9. A holder for a thin sensitized printing plate, comprising connected holding members for opposite edges of the plate, projecting reinforcements on said plate adjacent opposite edges thereof, and said holding members having edges on which the plate bears and recesses beyond said edges in which said reinforcements are seated for detachably securing the plate to said holding member. 125 130

- members, said edges of the holding members holding the plate with its outer face in a plane disposed outwardly beyond the plate securing means and the other parts of the holder.
10. A holder for a thin sensitized printing plate, comprising connected holding members for opposite edges of the plate, a projecting reinforcement on said plate adjacent one edge thereof, one edge thereof, one of said holding members having parts which said reinforcement engages for detachably securing the plate to said holding member, and means for moving said reinforcement endwise against a stop on said holding member for placing the plate accurately in a predetermined position on the holder.
11. A holder for a thin sensitized printing plate, comprising a frame having holding bars for opposite edges of the plate, means for securing opposite edges of the plate to said holding bars, screws for moving one of said bars relatively to the other bar, means for simultaneously turning said screws, and parts having screw connections with said screws and adjustably connected to said movable bar whereby said parts can be adjusted for causing a relatively different adjustment of the opposite ends of the bar.
- 30 12. A holder for a thin sensitized printing plate, comprising connected holding members for opposite edges of the plate, means for securing opposite edges of the plate to said holding members, a support on which the holder rests, and means for moving the holder laterally against a fixed part of the support to position the former accurately on the latter and securing the holder on the support.
- 40 13. A holder for a thin sensitized printing plate, comprising connected holding members for opposite edges of the plate, means for securing opposite edges of the plate to said holding members, a support on which the holder rests, means for moving the holder laterally against a fixed part of the support to position the former accurately on the latter, and means for pressing the holder firmly against the face of the support.
14. A holder for a thin flexible printing plate, comprising holding members for opposite edges of the plate, a projecting reinforcement on said plate adjacent one edge thereof, means for securing said reinforcement to one of said holding members, a part on said holding member against which said reinforcement is adapted to be moved endwise for securing the plate accurately in a predetermined position on the holder, and means for securing the opposite edge of the plate to said other holding member.
15. A holder for a thin flexible printing plate, comprising holding members for opposite edges of the plate, a projecting reinforcement on said plate adjacent one edge thereof, means for securing said reinforcement to one of said holding members, and means for securing the opposite edge of the plate to said other holding member, said holding members having edges on which the plate bears and which hold the plate with its outer face in a plane disposed outwardly beyond the plate securing means and other parts of the holder.
16. A holder for a thin flexible printing plate, comprising holding members for opposite edges of the plate, a projecting reinforcement on said plate adjacent one edge thereof, means for securing said reinforcement to one of said holding members, a part on said holding member against which said reinforcement is adapted to be moved endwise for securing the plate accurately in a predetermined position on the holder, means for securing the opposite edge of the plate to said other holding member, said holding members having edges on which the plate bears and which hold the plate with its outer face in a plane disposed outwardly beyond the plate securing means and other parts of the holder.

Witness my hand this 24th day of February, 1919.
